(57) **CLAIM**

The ornamental design for a dental light, as shown and described.

DESCRIPTION

FIG. 1 is a perspective view of a dental light showing my new design;

FIG. 2 is a front view of the dental light shown in FIG. 1;

FIG. 3 is a back view of the dental light shown in FIG. 1;

FIG. 4 is a left side view of the dental light shown in FIG. 1;

FIG. 5 is a right side view of the dental light shown in FIG. 1;

FIG. 6 is a top view of the dental light shown in FIG. 1; and,

FIG. 7 is a bottom view of the dental light shown in FIG. 1.

The broken lines shown in the drawings illustrate portions of the design and environmental structure, and form no part of the claimed design.
